UNITED STATES PATENT OFFICE.

EUGENE VOSBURGH, OF LONGMONT, COLORADO.

KNIFE-SETTING APPLIANCE.

Application filed June 18, 1921. Serial No. 478,585.

To all whom it may concern:

Be it known that I, EUGENE VOSBURGH, a citizen of the United States, residing at Longmont, in the county of Boulder and State of Colorado, have invented certain new and useful Improvements in Knife-Setting Appliances, of which the following is a specification.

This invention relates to an appliance for setting knives in knife boxes of beet-slicing machines and its main object is to provide an apparatus of simple and efficient construction which automatically adjusts the knives to a predetermined position with relation to each other and the boxes in which they are mounted.

An embodiment of my invention has been illustrated in the accompanying drawings in the various views of which like parts are similarly designated, and in which—

Figure 1 represents a front view of my improved knife-setting apparatus with a knife-box of a beet-slicing machine in position for the adjustment of its knives by the operation thereof;

Figure 2, a plan view of the apparatus shown in Figure 1;

Figure 3, a vertical section taken on the line 3—3, Figure 1, drawn to an enlarged scale;

Figure 4, a plan view of the rotary cutting element of a beet slicing machine;

Figure 5, an axial section of the element and the feed box with which it is associated, taken on the line 5—5, Figure 4.

Figure 6, a fragmentary section similar to that of Figure 3, and drawn to a reduced scale, showing a modification in the construction of the operating mechanism of the appliance, and

Figure 7, a face view of one of the knife-adjusting members of the device, looking in the direction of the arrow A, Figure 3.

It is essential in the process of sugar extraction from sugar beets that in the operation of a machine in which the beets are sliced into strips of V-shaped section, commonly known as cossettes, the product be of uniform width and thickness.

The types of beet slicing machines most commonly used in sugar factories comprise a rotary element carrying a series of detachably mounted boxes each of which contains a plurality of corrugated slicing knives. The knives are detachably fastened in the boxes so that they may be readily removed

to be sharpened when dulled in action, as frequently occurs in the operation of the machine, and inasmuch as the knives in the several boxes assembled on the rotary carrier cooperate in the production of the cossettes, it is of paramount importance that their position in the boxes be arranged in accordance with a predetermined uniform gage whereby to insure the true alinement of the cutting edges of the corresponding knives in the several boxes of the series assembled on the operating element of the machine.

It will be evident that in order to obtain the desired precise alinement of the knives their placement in the boxes requires careful adjustment and that the provision of a machine by which the knives are automatically positioned in their boxes in accordance with a predetermined uniform arrangement, is of great advantage in that it produces a dependable result at much saving of time and labor.

The knife-setting appliance shown in the drawings and hereinafter described is particularly adapted for use in setting knives in the boxes of a cutting element of the type illustrated in Figures 4 and 5 of the drawings. I desire it understood, however, that the mechanism is not limited in its use to this extent and that by slight modifications in the details of construction and the arrangement of its cooperating parts, it may be adapted for setting knives in boxes of slicing machines of different character without departing from the scope of the invention as defined in the hereunto appended claims.

The slicing element shown in Figures 4 and 5 consists of a disk A mounted for rotation about a vertical axis in an upright cylindrical container B into which the beets to be sliced are fed from above. The disk has a series of equidistantly spaced radial openings C to receive the knife-boxes E which are held in place by set screws F or other suitable means.

In the construction shown in the drawings each knife box contains three end to end adjoining knives G which are held in place by counter-sunk headed bolts H and nuts J. The knives consist of plates of tempered steel which have series of corrugations of V-shaped section extending into an edge thereof and sharpened at their open ends, and each box has an adjustable gage mem-

ber K which by its variable distance from the alined cutting edges of the knives determines the thickness of the cossettes cut in the operation of the machine.

5 The bolts H pass through longitudinally alined slots L in the back of the box and therewith alining, slantingly disposed slots M in the knives, which permit of both lateral and longitudinal adjustment of the knives 10 before the nuts are tightened on the bolts.

In the operation of the slicing machine, the disk on which the knife boxes are assembled, rotates about its vertical axis and by engagement of the forward cutting edges 15 of the knives with the lowermost beets in the container, cuts them into V-shaped strips of uniform width and thickness which pass through the space between the knives and the gage member K.

20 It will be readily understood that in order to constantly maintain this highly desirable degree of uniformity in the cross-sectional size of the cossettes produced by the machine, the cutting edges of the knives of 25 the various boxes must be accurately alined in circles concentric with the axis of rotation and that, provided the boxes are of uniform size and form and uniformly positioned on the disk, this result is dependent 30 on the proper position of the knives in the boxes, automatically obtained by means of the present setting appliance the construction and operation of which will now be described.

35 A rectangular supporting frame 5 of suitable form and proportions is for convenience fastened upon a table or work-bench 6 by means of machine bolts 7 extending through 40 openings in a projecting flange 8 of its base 9. The top of the support has a depressed seat 10 for the knife-box, and, at an end thereof, an upright abutment shoulder 12 which cooperates with an eccentric clamp at the opposite end of the seat to secure the knife-box in a predetermined position.

45 The clamp may be of any desired construction and has been shown to consist of a cylindrical block 13 mounted to move about a vertical eccentric spindle on the frame and provided with a handle to facilitate its rotation.

50 A shaft 14 rotatably mounted in bearings on upright members of the frame beneath 55 the top thereof, carries a plurality of arms 15 which in number and relative arrangement correspond with the knives in a knife box secured upon the support in the determinate position hereinbefore described and 60 shown in Figures 1 to 3 of the drawings.

65 The arms extending upwardly from the shaft are provided at their upper ends with corrugated dies 16 which are adapted to mesh with the corrugations of the knives of the knife box when in the operation of the

machine they are brought in engagement therewith by rotation of the shaft.

The arms are extended below the shaft on which they are mounted to provide contact faces 17 for cams 18 on a shaft 19 70 which is supported in bearings on the upright members of the frame in parallel relation to the other.

A lever arm 20 extending laterally from the cam shaft is through the medium of a 75 rod 21, connected to a treadle 22 which is hinged as at 23 to a part at the lower portion of the bench or table on which the setting appliance is supported.

A spring 24 associated with the hinge 80 serves to yieldingly maintain the treadle and therewith connected parts in their normal position of rest in which the dies on the arms 15 are separated from the knives in the knife-box as shown in full lines in 85 Figure 3, and a ratchet bar 25 on the bench cooperates with a detent 26 on the treadle to secure the latter in a depressed condition against the action of the spring.

A spring 27 coiled around the cam shaft 90 in connection with an adjacent part of the supporting frame cooperates with the spring of the hinge to restore the parts to their normal position when the detent on the treadle is released from the teeth of the 95 ratchet bar and a similar spring 28 applied to the shaft 14 serves to automatically separate the arms from the knives in the knife-box after the operation is completed.

100 Bars 29 extending upwardly from the back of the frame 5 in rigid connection therewith, are bent angularly above the top of the same to provide abutments for the knives in the knife-box when they are engaged by the dies on the rocker arms in the operation of the 105 appliance.

110 In the modified construction of the operating mechanism shown in Figure 6, the cam shaft has been eliminated and the rod 21 connected with the treadle, is at its upper end pivotally attached to a crank arm 30 directly mounted on the rocker shaft 14.

115 In the operation of my invention a knife-box is placed in an upright position in the seat at the top of the frame between the stationary shoulder 12 and the eccentric clamp which secures it against displacement.

120 The bolts which fasten the knives in the knife-box are loosened to permit of the adjustment of the knives when engaged by the dies on the arms 15, and a gage 31 is placed upon the seat of the frame, as best shown in Figure 3 to support the knives at a determinate distance above the edge of the adjustable gage K of the box.

125 The gage 31 consists of a flat bar of metal which stands loosely on the frame to determine the vertical position of the knives, and by providing a number of these bars made in different widths, the knives may be ad-

justed to cut cossettes of any desired thickness or the knives of boxes of different dimensions may be adjusted in accordance with a predetermined standard.

5 After the knife box and the gage bar are relatively positioned as shown and described, the operator by depression of the treadle brings the dies 16 in engagement with the loosely supported knives, as shown in broken 10 lines in Figure 3, and in full lines in Figure 2.

The first light contact of the dies with the knives causes the latter to drop upon the gage bar 31 and continued pressure on the 15 arms 15 brings the corrugated dies in mesh with the corresponding corrugated cutting portions of the knives and causes the latter to shift laterally to a position with relation to each other and an end of the box in which 20 they are supported, predetermined by the relative positions of the arms and the dies.

After the knives have thus been placed the treadle is locked in its depressed condition by the engagement of its detent with the 25 ratchet bar and the nuts on the bolts of the knife boxes are tightened until the knives are securely fastened in their adjusted position. After the treadle is subsequently released the springs automatically return the 30 cooperating parts of the mechanism to their original position.

It will be apparent that by the cooperation of the means for holding each knife-box in the same position with relation to the operating mechanism of the appliance, the dies which are immovably arranged with relation to each other, and a gage bar of standard width, the knives of the several uniformly constructed knife-boxes of a beet-slicing machine, may be uniformly arranged with relation to each other and the ends of the boxes and that when the boxes are subsequently fastened in the openings of the rotary carrier of the machine in contact with concentric shoulders at the ends thereof, the cutting edges of the knives will invariably lie in circles concentric to the axes of rotation to produce cossettes of uniform width and thickness.

50 While I have shown my improved knife-setting apparatus in the best and simplest form at present known to me, I desire it understood that I do not limit myself to the exact construction shown in the drawings and 55 hereinbefore described, and that variations in the construction and arrangement of its parts may be resorted to without departing from the spirit and scope of my invention.

What I claim and desire to secure by 60 Letters-Patent is:

1. A knife-setting appliance comprising a support having means determining the position of a knife-box thereon, an element adapted to engage a face of knives loosely held in the box for their lateral adjustment;

and abutment means engaging the opposite faces of the knives to resist pressure of the element.

2. A knife-setting appliance comprising a support having means determining the position of a knife-box thereon, an element adapted to engage knives loosely held in the box for their adjustment to a determinate position, and foot-operated means for the actuation of said element. 75

3. A knife-setting appliance comprising a support having means determining the position of a knife-box thereon, a shaft, corrugated dies carried on the shaft and adapted to engage knives loosely held in the box by 80 a partial rotation thereof, and means to actuate the shaft.

4. A knife-setting appliance comprising a support having means determining the position of a knife-box thereon, a shaft, corrugated dies carried on the shaft and adapted to engage knives loosely held in the box by 85 a partial rotation thereof, means to actuate the shaft, and a spring yieldingly holding the shaft in its normal position of rest. 90

5. A knife-setting appliance comprising a support having means determining the position of a knife-box thereon, a shaft, corrugated dies carried on the shaft and adapted to engage knives loosely held in the 95 box by a partial rotation thereof, and foot-operated means to actuate the shaft.

6. A knife-setting appliance comprising a support having means determining the position of a knife box thereon, a shaft, corrugated dies carried on the shaft and adapted to engage knives loosely held in the 100 box by a partial rotation thereof, a treadle, and an operative connection between the treadle and the shaft. 105

7. A knife-setting appliance comprising a support having means determining the position of a knife-box thereon, a shaft, corrugated dies carried on the shaft and adapted to engage knives loosely held in the 110 box by a partial rotation thereof, a spring-held treadle, and an operative connection between the treadle and the shaft.

8. A knife-setting appliance comprising a support having means determining the 115 position of a knife-box thereon, a shaft, corrugated dies carried on the shaft and adapted to engage knives loosely held in the box by a partial rotation thereof, a cam acting upon the shaft to effect its rotary motion, a lever-arm connected with the cam, and a treadle operatively connected with the lever-arm. 120

9. In an appliance for setting knives in a box having a discharge slot along the cutting edges thereof, a support for the box, an element for the lateral adjustment of the knives in the box, and means co-operating with said element to gage the width of the discharge slot. 125 130

10. In an appliance for setting knives in a box having a discharge slot along the cutting edges thereof, a support for the box, an element for the lateral adjustment of the knives in the box, and means adapted to aline the cutting edges of the knives and to simultaneously gage the width of the slot, in the operation of the adjusting element.
11. In an appliance for setting knives in a box having a discharge-slot along the cutting edges thereof, a support for the box, an element for the lateral adjustment of the knives in the box, and a removably supported gage bar for engagement with the cutting edges of the knives, to aline said

cutting edges and determine the width of the discharge slot.

12. In an appliance for setting knives in a box having a discharge-slot along the cutting edges thereof, a support for the box, an element for the lateral adjustment of the knives in the box, and a removable gage bar resting on the support in engagement with the cutting edges of the knives, to aline said cutting edges and determine the width of the discharge slot.
